UNITED STATES PATENT OFFICE.

ERNEST CONRAD WEGMAN AND WILLIAM ALFRED SOUTHWICK, OF CHICAGO, ILLINOIS, ASSIGNORS TO WESTERN ELECTRIC COMPANY, INCORPORATED, OF NEW YORK, N. Y., A CORPORATION OF NEW YORK.

APPARATUS FOR WORKING STRAND MATERIAL.

Application filed June 13, 1924. Serial No. 719,697.

This invention relates to apparatus for working strand material.

The primary object of the invention is to provide apparatus for twisting two strands together in such manner that during the twisting operation the strands are frictionally held so that for any given length of pair the length of each strand constituting a pair is the same.

10 Another object of the invention is to provide apparatus for simultaneously assembling two pairs of strands, twisting the pairs individually and twisting the said pairs together to form a quad.

15 A further object of the invention is to provide an improved apparatus for assembling four insulated electrical conductors to form a quadded cable, each quad comprising two twisted pairs, the pairs being twisted together.

20 A still further object of the invention is to provide apparatus for forming quads in such manner that for any given length of a pair the length of each wire constituting the pair is the same.

25 Apparatus embodying the invention may be used to advantage in forming "quadded cable" which is suitable for phantom working, such a cable being used primarily in telephone systems. For a complete disclosure of the specific construction, and functions of a "quadded cable", reference is made to U. S. patent to Anderegg and Mougey, No. 1,271,824.

30 Heretofore in the manufacture of quadded cable it has been the usual practice first to bind together a pair of conductors by means of a strand wrapping, this binding operation serving to hold the conductors in 35 definite linear relation with respect to each other. An apparatus for performing this binding operation is disclosed in Patent No. 1,565,863, issued Dec. 15, 1925, to C. G. Stoll. Two pairs bound together in the manner just described were then twisted together to form a quad.

40 The primary object of this invention is to provide apparatus for producing quadded cable in which the binding operation just referred to is dispensed with but at the same time the quadded cable produced has the same balance which was made possible by the binding operation just referred to.

45 Although the invention is particularly adapted for the manufacture of "quadded cable" for use in telephone systems, it is to be understood that the invention is not confined to this use and is to be limited only by the spirit and scope of the appended claims.

50 Other objects and advantages of the invention will appear from the following detailed description taken in connection with the accompanying drawings.

55 An apparatus made in accordance with the present invention for manufacturing "quadded cable" without the use of a binding for the individual pairs, comprises means for supplying four insulated conductors, means for grouping these conductors together in pairs and maintaining them in definite linear 60 relation with respect to each other, and further means for twisting together these pairs of insulated conductors to form the quads while still maintaining the length of each conductor constituting the pair the same, a 65 plurality of quads being stranded together in the usual manner to form a cable.

70 In the accompanying drawings, which illustrate an apparatus by which the method may be performed,

75 Fig. 1 is a front elevation of such an apparatus;

80 Fig. 2 is a side elevation thereof, the framework of the machine being omitted;

85 Figs. 3 and 4 are fragmentary and enlarged detail views illustrating the means for grouping the four conductors into two pairs and maintaining the pairs in definite linear relation with respect to each other;

90 Figs. 5 and 6 are a side elevation and vertical section respectively of the mechanism disclosed in Fig. 3; and

95 Fig. 7 is an enlarged detail view.

It is believed that the improved method will be readily understood by a description 100 of an apparatus by which it may be performed.

105 Referring now to the drawings in detail in which like reference numerals designate similar parts throughout the several views, 10 represents vertical uprights and 11 and 12 horizontal spacing members constituting a suitable framework for supporting the various elements of the apparatus.

110 Carried by the spacing bars 11 and 12 is a vertically disposed shaft 13 positioned ap-

- proximately midway between the vertical uprights 10 of the framework. Secured to the shaft 13 adjacent to the lower end thereof is a cross-bar 14 and positioned thereabove and secured to the shaft 13 are two cross-bars 15 and 16. The ends of the cross-bars 14 and 15 are provided with suitable bearings to receive stud shafts 42 and 43 secured to the opposite ends of yokes 17 and 18. The yokes 17 and 18 are identical and the vertical walls thereof are provided with suitable bearings to receive horizontally disposed and removable shafts 19 and 20 respectively. Rotatably mounted upon the shaft 19 and within the yoke 17 are two supply spools 21 and 22 so disposed on the shaft that as the strand material thereon is withdrawn from the spools they are caused to rotate in opposite directions. The adjacent hubs of the spools 21 and 22 are mounted in contact with each other so that as they rotate in opposite directions in feeding the strand material therefrom the friction exerted between these hubs will be sufficient to place a drag upon the spools making the usual form of tension control unnecessary. Positioned upon the shaft 20 are two supply spools 23 and 24 which are mounted similarly to the supply spools 21 and 22.
- Associated with the yoke 17 and mounted directly above it is a capstan 25 which is rotatably mounted upon a horizontally disposed shaft 26 carried by a spaced pair of V-shaped arms 27 (Figs. 3 and 5). Each arm 27 has integral with its upper end a semi-circular collar 28 and integral with its lower end a semi-circular collar 29. The collars 29 are fitted around the end of the stud shaft 42 of the yoke 17 which shaft projects above the cross-bar 15. The semi-circular portions 29 are held together in the usual manner by bolts 31 and are fastened to the stud shaft 42 by means of keys 32. The semi-circular portions 28 of the arms 27 are fitted around the projecting end of a bushing 133 rotatably mounted in the cross-arm 16 (Fig. 6), the semi-circular portions being held together by bolts 33 which clamp the portions 28 on the bushing. Associated with the yoke 18 is a capstan 34 which is identical to the capstan 25 and mounted between the cross-bars 15 and 16 in exactly the same manner.
- The shaft 13 has secured to its lower end a beveled gear 35 which meshes with a beveled gear 36 fastened upon a shaft 37 which may be rotated by any suitable source of power (not shown). Also fastened upon the shaft 13 and mounted above the beveled gear 35 is a gear 38 having meshing therewith and on opposite sides thereof pinions 39 and 40 suitably rotatably mounted upon stud shafts carried by the cross-arm 41. Meshing with the pinion 39 is a gear 41 secured to the lower end of the stud shaft 42 carried by the yoke 17. Mounted upon a stud shaft 43 carried by the yoke 18 is a gear 44 meshing with the gear 40.
- Mounted upon the spacing bar 11 is a suitable gear housing 45 containing a gear train for actuating a capstan 46 which serves to draw the quadded strand from the machine and deliver it to a suitable take-up device (not shown). The gear train within the housing 45 is driven by shaft 13 whereby the capstan 46 is driven in definite relation with the rotation of the shaft 13 and yokes 17 and 18.
- In the operation of the machine the shaft 13 is caused to revolve by the gears 35 and 36, revolving with it the yokes 17 and 18. These yokes however also rotate on their own axes driven by the gears 41 and 44 actuated through the gear train previously described. Since the arms 27 carrying the capstans 25 and 34 are secured to the stud shafts of the yokes 17 and 18, these capstans are caused to rotate around a vertical axis at the same speed as the yokes.
- The strand materials upon the supply spools 21 and 22 are drawn upwardly by the capstan 25 through the tubular stud shaft 42 associated with the yoke 17 and through a die 48 mounted within the upper end of the shaft 42, the opening in the die being of such shape as to position the two strands side by side. From the die 48 the strands pass upwardly between two longitudinally spaced and vertically disposed tubes 49 and around the capstan 25 the said strands having their sides in engagement with each other. From the lower portion of the periphery of the capstan the said strands are passed upwardly through the tubes 49 and thence through the bushing 133 (Figs. 3 and 6). The tubes 49 are carried by a horizontally disposed bar 50 secured to the lower end of two parallel disposed arms 51 the upper ends of which are fastened to the semi-circular portions of the arm 27 by one of the bolts 33.
- In order to prevent any slipping of the strands longitudinally relative to each other as they pass around the capstan a roller 52 formed of rubber or any other suitable material is pressed in contact with the strands, this roller being horizontally disposed and mounted on a shaft 53 carried in the upper ends of parallel arms 54 pivoted at their lower ends upon studs 55 carried by the arms 27. The roller 52 is pressed against the strands on the capstan by tension springs 56 strained between the arms 54 and the V-shaped arms 27. As the strands pass upwardly from the capstan and through the bushing 133 they are fed through a polishing die 149 mounted within the bushing and thence upwardly through a chuck 57 carried by the shaft 13. Since the capstan 25 rotates with the yoke 17 and relative to the shaft 13 and chuck 57, a twist is put in the

strands between the die 149 and the chuck 57 and the said strands enter the interior of the chuck, in a manner hereinafter to be described, as a twisted pair. The strands upon 5 the supply spools 23 and 24 mounted within the yoke 18 are fed upwardly and twisted into a pair in a manner similar to the strands fed from the supply spools 21 and 22 as previously described. As previously 10 stated, from the polishing dies mounted within the bushings carried by the cross-bar 16 the twisted pairs are fed upwardly through a chuck 57 carried by the shaft 13, this chuck having two diagonally arranged 15 openings 58 which meet in a vertically disposed opening 59. As the twisted pairs of strands pass through the chuck 57 they are twisted around each other at a point between the chuck and the capstan 46, whereby the 20 material fed by said capstan to the take-up device is in the form of a quad. The length of twists put in the individual pairs and the length of the twists between the two pairs may be controlled as desired by the substitution 25 of the proper size gears in the gear train including the gears 39, 40, 41 and 44. Since the apparatus is particularly designed for producing the type of cable in the Anderegg and Mougey patent above referred to, 30 this gear ratio is of such a character that the twists in the quad are shorter than the twists in the pairs constituting the quad.

In the apparatus described quadded cable may be produced without the use of a binding for the individual pairs since the capstans 25 and 34 and associated elements, 35 namely, the tubes 49 and roller 52 serve to maintain a definite lineal relation between the strands constituting a pair which is an essential requisite in the production of quadded cable having the electrical characteristics desired.

What is claimed is:

1. In an apparatus for working strands, 45 means for twisting a pair of strands together and friction means associated with said twisting means for maintaining the length of each strand constituting the pair the same, and means for twisting said pairs together to form a quad.

2. In an apparatus for working strands, a pair of yokes, a pair of supply spools mounted in each yoke, a capstan associated with each yoke and means for drawing off the 55 worked strands.

3. In an apparatus for working strands, a pair of yokes, a pair of supply spools mounted in each yoke, a capstan associated with each yoke, means pressed against the periph-

ery of each capstan and means for drawing 60 off the worked strands.

4. In an apparatus for working strands, a plurality of rotatable elements, two sources of supply of strand material carried by each of said rotatable elements, means for rotating 65 said elements to twist together strands from said supplies into twisted pairs, means for maintaining the length of each strand constituting each pair the same and means for twisting the twisted pairs together. 70

5. In an apparatus for working strands, a plurality of rotatable elements, two sources of supply of strand material carried by each of said rotatable elements, means for rotating 75 said elements to twist together strands from said supplies to form two twisted pairs, gripping means for maintaining the length of each strand constituting each pair the same and means for twisting said twisted pairs together. 80

6. In an apparatus for working strands, a rotatable element, two sources of supply of strand material carried by said element, means for rotating said element to twist together strands from said supplies, means 85 comprising a rotary element disposed between said rotatable element and the point where the twisting takes place, said means maintaining the length of each strand constituting a pair the same. 90

7. In an apparatus for working strands, a rotatable element, two sources of supply of strand material carried by said element, means for rotating said element to twist together strands from said supplies, means 95 comprising a rotary element and a gripping element associated therewith for maintaining the length of each strand constituting a pair the same.

8. In an apparatus for working strands, a rotatable element, two sources of supply of strand material carried by said element, means for rotating said element to twist together strands from said supplies, means comprising a revolvable element actuated by 100 the passage of the strands thereover for maintaining the length of each strand constituting a pair the same. 105

9. In an apparatus for working strands, a pair of yokes, a pair of supply spools mounted in each yoke, a capstan having a spring pressed roller cooperating therewith associated with each yoke and means for drawing off the worked strands. 110

In witness whereof, we hereunto subscribe 115 our names this 31st day of May, A. D. 1924.

ERNEST CONRAD WEGMAN.

WILLIAM ALFRED SOUTHWICK.
